By his Attorney ## UNITED STATES PATENT OFFICE.

T. RAYMOND ARDEN, OF NEW YORK, N. Y., ASSIGNOR, BY MESNE ASSIGNMENTS, TO
LOUIS MARX, OF NEW YORK, N. Y.

MECHANICALLY-OPERATED DANCING TOY.

Application filed January 19, 1924. Serial No. 687,172.

To all whom it may concern:

Be it known that T. T RAYMOND ARDEN, a citizen of the United States of America, residing at New York city, New York, have invented new and useful Improvements in Mechanically-Operated Dancing Toys, of which the following is a specification.

My invention relates to a toy in the form of a dancing figure, in which the oscillating motion of the body and limbs is controlled by a spring actuated escapement mechanism.

The object of the invention is to provide a simply constructed toy of this character which may be cheaply produced, and which may be easily operated by a young child.

The invention is illustratively exemplified in the accompanying drawings, in which, Figure 1 is a side elevational view of my improved dancing toy, and Figure 2 is a front elevational view of the same; Figure 3 is a sectional view of the device taken on the lines 3—3 of Figure 1, and Figure 4 is a sectional view of the toy taken on the lines 4—4 of Figure 2; Figure 5 is a transverse sectional view of the toy taken on the lines 5—5 of Figure 3; Figure 6 is a section taken on the lines 6—6 of Figure 4; and Figure 7 is a sectional view of the power spring core showing the means used to connect the parts.

Referring to the drawings, 10 denotes a suitable base, comprising a circular member having a depending peripheral flange 11 and a radially disposed key fin 12 extending between the inner periphery of the flange and center of the member. The base 10 is adapted to support the dancing figure and its operating mechanism in an upright position, and also due to its specific arrangement in connection with the power mechanism the base is used to wind the power spring, as hereinafter described.

A square winding shaft 13 is fixed at its lower end to the center of the base 10, and projects in upright position to support and guide the movements of the figure. The figure, according to the present design, is shaped to represent a male dancer and consists of a body portion 14 having the head 15 provided with an opening 16 in the crown thereof to loosely embrace the free end of the winding shaft 13. The body is preferably constructed of stamped sheet metal halves attached together at their edges to form a hollow member in which the operat-

ing mechanism is housed. Both sides of the body portion 14, just below the shoulders, are provided with arm holes 16' to receive a pair of arms 17. The arms 17 are slightly curved pieces of metal provided with a T-shaped projection 18, at their upper ends to be inserted into the arm holes 16. The operation of inserting the projections 18 into the holes 16 is performed by bending the cross head of the T over the stem portion, thereafter placing the end of the latter through the hole 16 and then unfolding the cross head whereupon the arm is securely attached in position, i. e. it may be moved in substantially any position without becoming unattached from the body portion 14. The lower or hand portion of each arm 17 projects to the lower open end of the body 14, as shown in Figure 2, and overlies an open slot 19 cut in each side of the said body. The legs 20 of the toy are suspended from beneath the body 14 adjacent the slots 19, in a manner hereinafter described in connection with the description of the operating mechanism. Each leg comprises an upper and lower section 21 and 22, the former being a hollow metal part flattened at its upper end and provided with an eye 23 which remains in constant register with the adjacent slot 19. The lower end of the upper section 21 is divided to form pivot prongs 24 which receive and support the lower section 22. The lower section or joint 22 is also a hollow metal part having a ball shaped upper end embraced by the prongs 24 and a lower end portion shaped to represent a shoe 25, which is provided under the heel with an integral spur like projection 26, adapted to engage the upper surface of the base 10 and to establish a pivot point for the lower section 22, when, in the course of operation of the figure, the lowering of the complete leg will cause the two sections to rock at the knee joint about the pivots 24. The condition just described is shown in dotted lines in Figure 2, and will be more fully described hereinafter.

Referring now to the operating mechanism and particularly to Figures 3 to 6, inclusive, 27 denotes a crank arm or bracket rigidly secured to the shaft 13 at a point short of the upper end, the length of shaft beyond the bracket being of sufficient length to be received by the opening 16 and to

guide the body portion 14 in its vertical movement. The bracket 27 comprises a flat metal strip of material having its upper end bent at right angles to form a rest or support for the body 14 in its lowest position, the bent portion being provided with a square opening to embrace the shaft 13; a straight portion projecting adjacent the shaft and another lower angularly bent portion having a square opening to again embrace the shaft at a lower elevation. The lower bent portion projects in the same direction and is parallel to the upper bent portion, and at its end the lower part is bent downwardly to provide an anchor 28 for one end of the power spring 29.

The spring 29 coils about a sleeve 30, which loosely surrounds the shaft 13, and which is provided at its upper end with a series of tongues 31 engaged in a cap piece 32. The cap comprises a central dome portion 33, which abuts the under surface of the bracket 27, and which is provided with a center opening to loosely embrace the winding shaft 13. The tongues 31 engage the cap 32 through openings in the base of the dome portion, the lower part of the cap being curved upwardly and outwardly to form a seat 34 against which the spring 30 is adapted to center when the latter is unwound. The purpose of the dome 33 is to provide a bearing surface for the sleeve 30 against the bracket 27, which bearing surface will offer the minimum amount of friction surface possible. The tubular sleeve 30 projects a substantial distance over the shaft 13 and at its lower end it carries an escapement wheel 35 to which the opposite or lower end of the spring 29 is attached.

Disposed within the hollow body 14 adjacent the lower open end thereof and on a plane corresponding with that of the side slots 19, is the escapement device operated by the escapement wheel 35. This device is carried by a frame 36 comprising a rectangular lower box portion 37 loosely surrounding the shaft 13 and supported upon a collar 38 integrally connected to the shaft. The opening in the box portion 37 is disposed laterally of the figure and its axis is directed from front to back, the side walls of this portion being arranged just in back of the slots 19, as shown in Figure 4. The portion of the shaft 13, between the bottom and top walls of the box portion 37, carries a ratchet wheel 39, which is provided with a square central opening to embrace the shaft, and which is held in contact with the under surface of the said top wall by means of a spring 40, the coils of which surround the shaft and seat at one end against the bottom wall and at the other against the wheel. The ratchet wheel 39 in the present instance

comprises a flat piece of springy metal having two oppositely arranged teeth 41, which move in a circular path, by the winding operation of the shaft, and ride up and over a series of lugs 42 struck up in the upper wall of the frame and disposed in a circular arrangement to be engaged by the teeth 41. Following the winding operation of the stem or shaft 13 the spring 29 is held from reversing the rotation of the shaft 13 by engagement of the teeth 41 against the closed end of the lugs 42, as illustrated in Figure 6.

The upper wall of the box portion 37 projects laterally, a substantial distance, on both sides of the center and is then bent upright at right angles to the plane of the wall to provide a front and back wall 43 and 44, the former wall being provided with a spring projection 45 yieldably bearing downwardly against the escapement wheel 35 to hold the latter in position against a tubular sleeve 46. The sleeve 46 loosely surrounds the shaft 13 and provides a spacing piece to support the escapement wheel 35.

The escapement proper comprises a beam 47 disposed between the two upright walls 43 and 44 and provided with flat axial projections 48 at opposite ends to be supported in bearings 49 in the walls. The bearings 49 are virtually openings in the front and back walls 43 and 44, which openings are provided with upper and lower projections 50 which extend towards each other so as to allow an intervening space equal to the gage of the flat projections 48. This manner of supporting the beam 47 gives a positive amount of clearance in which the beam may oscillate. The center of the beam 47 is provided with an elongated opening 51 to loosely receive the sleeve 46; and on alternate edges of the beam the metal is turned upright at right angles to the plane thereof to provide pallets 52 adapted to be engaged by the inclined edges of the escapement wheel teeth 53, thereby imparting an oscillatory movement to the beam. The edges of the beam adjacent the back of the toy are bent upright to receive a balance pendulum 54, the latter being provided to offset the weight of the body portion 14 and legs 17 which are being lifted by movement of the beam, the lifting operation being effected by a pair of oppositely projecting arms 55 disposed transversely of the beam. The arms 55 are preferably an integral part of the beam 47 and of sufficient length to project through the eyes 23 of the upper leg sections 21, slots 19 in the body 14, and at their ends to engage the inside surface of the hand portions of the arm 17, as illustrated in Figure 4.

Following is a description of the operation of the device: By holding the body

portion 14 in one hand and turning the base 10 in the proper direction with the other hand, the coils of the spring 29 are tightened. The body being held, the teeth 53 will remain at rest by engagement of one of the pallets 52 against the straight edge of a tooth, and the beam 47 will be held against oscillation. The ratchet wheel 39 permits the winding shaft 13 to be rotated forwardly, i. e. in a direction to tension the coils and reverse rotation of such shaft is prevented by engagement of the ratchet wheel 39 with the closed end of the lugs 42.

15 When the body is released and the base 10 is placed upon a supporting surface, the energy stored in the spring 29 will become effective to revolve the escapement wheel 35 in the direction of the upward inclination of the teeth 53, the latter teeth being adapted to coact with the pallets 52, thereby rocking the beam 47 on its pivotal supports 48. Owing to the almost perfect balance of the beam maintained by the pendulum 54 on 20 one side of the pivotal axis and the weight of the body on the other side, it requires barely any power for the actuation of the device and consequently the toy will remain in operation until the spring is fully un- 25 wound.

The oscillation of the beam 47 causes the arms 55 to alternately raise and drop and as each arm moves upwardly the leg being hung therefrom moves to a corresponding 30 elevation and in so doing it leaves the surface of the base 10. In its upward movement the arm 55 engages the top edge of the slot 19 and continues to rise with the body portion 14 which is guided about the 35 free upper end of the shaft 13. It is to be noted that the ends of the arms 55, during oscillatory movement, move through arcs which intersect the normal positions of the arms 17; and as a consequence the ends of 40 the arms 55 abut the inner surface of arms 17 and cause the latter to be pushed outwardly away from the body 14 and about their sockets 18. When these movements 45 are performed in rapid succession the toy will have all the appearances of a dancing figure, i. e. the body portion will vibrate in a vertical direction while the legs will be alternately lifted and dropped thereby causing the pointed projections to engage the 50 base 10 and the upper and lower joints to pivot at their knee joint, all of which movements are being carried out while the arms 55 are being thrown outwardly from the sides of the figure.

60 What I claim and desire to secure by Letters Patent is:—

1. A dancing toy comprising a toy figure adapted to be actuated, motor means within the toy figure associated therewith for actuating the same, and means supporting the

toy figure operatively connected to said motor means for winding the same.

2. A dancing toy comprising a toy figure, including a body portion and leg portions, motor means within the body portion of the 70 toy figure connected to said leg portions for actuating the same, and means supporting the body portion of the toy figure and operatively connected to said motor means for winding the same. 75

3. A dancing toy comprising a toy figure adapted to be actuated into dancing action, motor means within the toy figure associated therewith for actuating the same, and means supporting the toy figure and the 80 motor means operatively connected to said motor means for winding the same.

4. A dancing toy comprising a toy figure having a body portion and separate leg portions, spring actuated means for supporting 85 and oscillating said leg portions and means supporting the body portion and the spring actuated means operatively connected to the latter for winding the same.

5. A dancing toy comprising a toy figure 90 having a body portion and separate leg portions, spring actuated means for supporting and oscillating said leg portions and means including a base and an operating shaft supporting the body portion and the spring 95 actuated means connected to the latter for winding the same.

6. A dancing toy comprising a toy figure having a body portion and separate leg portions, spring actuated means within the body 100 portion for supporting and oscillating said leg portions and means supporting the body portion and the spring actuated means connected to the latter for winding the same. 105

7. A dancing toy comprising a toy figure having a body portion, arm portions loosely jointed to the body portion, and separate leg portions disposed beneath the body portion, spring actuated means for vibrating the arm 110 portions and for supporting and oscillating the leg portions, and supporting means for the body portion connected to the spring actuated means for winding the same.

8. A dancing toy comprising a toy figure having a body portion, arm portions loosely 115 jointed to the body portion, and separate leg portions disposed beneath the body portion, spring actuated means for vibrating the arm portions and for supporting and oscillating the leg portions, and supporting means for the body portion and the spring actuated means connected to said spring actuated means for winding the same. 120

9. A dancing toy comprising a toy figure having a body portion, arm portions loosely jointed to the body portion, and separate leg portions disposed beneath the body portion, spring actuated means for vibrating the arm 125 portions and for supporting and oscillating the leg portions, and supporting means for 130

the body portion including a base and an operating shaft connected to the spring actuated means for winding the same.

10. A dancing toy comprising a toy figure having a body portion, spring actuated means housed by the body portion for actuating the toy figure, and supporting means comprising a winding shaft projecting axially through the said body portion and a crank member carried by the shaft connected to the spring actuated means whereby rotary movement of the shaft and crank will energize the said spring actuated means.

11. A dancing toy comprising a toy figure having a body portion, spring actuated means housed by the body portion for actuating the toy figure, and supporting means comprising a winding shaft projecting axially through the said body portion connected to the spring actuated means whereby rotary movement of the shaft will energize the said spring actuated means.

12. A dancing toy comprising a toy figure, spring actuated means housed by the toy figure for actuating the same, and supporting means for the toy figure comprising an upright shaft projecting axially through the toy figure and connected to the spring actuated means and a base member to which said shaft is rigidly mounted, the base member being adapted to support the toy figure in upright position.

13. A dancing toy comprising a toy figure, spring actuated means housed by the toy figure for actuating the same, and supporting means for the toy figure comprising an upright shaft projecting axially through the body of the toy figure and having a crank member connected thereto at its upper end, said crank member being connected to the spring actuated means, and a base member in which said shaft is rigidly mounted, said base member being adapted to support the toy in upright position and to be grasped by the hand to rotate the shaft to wind the spring actuated means.

14. A dancing toy comprising a toy figure including a body portion, a spring actuated means for operating the toy figure, and means for supporting the toy figure and for winding the spring actuated means, the said supporting means comprising an upright shaft projecting axially through the body portion and through an opening in the head thereof and having an integrally connected crank member connected with the spring actuated means to tension the spring of the latter, and a base member in which said shaft is rigidly mounted, the base member being adapted to support the toy in an upright position.

15. A dancing toy comprising a toy figure including a body portion, spring actuated means for operating the toy figure, and means for supporting the toy figure and for

winding the spring actuated means, the said spring actuated means comprising an oscillating member adapted to alternately engage opposite sides of the body portion to vibrate the latter.

16. A dancing toy comprising a toy figure including a body portion and arms, spring actuated means for operating the toy figure, and means for supporting the toy figure and for winding the spring actuated means, the said spring actuated means comprising an oscillating member having a pendulum balance and projecting pallets on opposite sides and projecting arms having their paths of movement through slots in opposite sides of the body portion to alternately engage the arms to vibrate the latter, an escapement wheel having teeth adapted to engage the pallets and oscillate the said member, a spring disposed axially of the supporting means and connected at one end to the escapement wheel, and a crank arm carried by the supporting means and connected to the opposite end of the spring, whereby rotary movement of the crank with respect to the said wheel will tension the spring.

17. A dancing toy comprising a toy figure having a body portion and separate leg portions, spring actuated means for supporting and oscillating the said leg portions, and means supporting the body portion and the spring actuated means connected to the latter for winding the same, the said spring actuated means comprising an oscillating member having oppositely extending arms projecting through openings in the leg portions and thereafter through slots in the body portion, whereby oscillatory movement of the member will impart simultaneous vibratable movement in both the legs and body portion.

18. A dancing toy comprising a toy figure having a body portion and separate leg portions, spring actuated means for supporting and oscillating the said leg portions, and means supporting the body portion and the spring actuated means connected to the latter for winding the same, the said supporting means including a base platform adapted to maintain the toy in vertical position, said leg portions comprising jointed members, the lower members of which are adapted to engage with the top of the platform during oscillatory movement of the said leg portions.

19. A dancing toy comprising a toy figure having a body portion and separate leg portions, spring actuated means for supporting and oscillating the said leg portions, and means supporting the body portion and the spring actuated means connected to the latter for winding the same, the said supporting means including a base platform adapted to maintain the toy in

vertical position, said leg portions comprising jointed members, the lower members of which are adapted to engage with the top of the platform during oscillatory movement of the said leg portions, and an integral pointed projection disposed under the foot portion of each lower leg member and adapted to pivot on the said platform to cause the legs to bend at their joints when 10 in their lowermost position.

20. A dancing toy comprising a toy figure having a body portion and arm portions loosely jointed to said body portion, of separate leg portions disposed beneath the 15 said body portion, spring actuated means for vibrating the arm portions and for supporting and oscillating the leg portions, and supporting means for the body portion connected to the spring actuated means for winding 20 the same, the said spring actuated means including an oscillatable member having projecting arms to receive and support the said leg portions, the said arms being arranged to project through slots in the 25 body and to move against the said loosely jointed arm portions of the body to cause a swinging movement of the arms with respect to the body.

21. An actuating mechanism of the class 30 described comprising a winding shaft having a crank disposed at its upper end, a sleeve disposed about said shaft and having a toothed escapement wheel at its lower end, a coil spring disposed about the said 35 sleeve and attached at opposite ends to the crank and escapement wheel respectively, an escapement beam having pallets to be engaged by the teeth of the escapement wheel, and a frame supported loosely on 40 said shaft and provided with bearings in which the said beam is mounted.

22. An actuating mechanism of the class 45 described comprising a winding shaft having a crank disposed at its upper end, a sleeve disposed about said shaft and having a toothed escapement wheel at its lower end, a coil spring disposed about the said 50 sleeve and attached at opposite ends to the crank and escapement wheel respectively, an escapement beam having pallets to be engaged by the teeth of the escapement wheel, and a frame supported loosely on said shaft and provided with bearings in which the 55 said beam is mounted, said frame being provided with a spring projection adapted to yieldably engage the upper surface of said escapement wheel to hold the teeth in the path of the pallets.

23. An actuating mechanism of the class 60 described comprising a winding shaft having a crank disposed at its upper end, a sleeve disposed about said shaft and having a toothed escapement wheel at its lower end, a coil spring disposed about the said sleeve

and attached at opposite ends to the crank 65 and escapement wheel respectively, an escapement beam having pallets to be engaged by the teeth of the escapement wheel, a frame supported loosely on said shaft and provided with bearings in which the said 70 beam is mounted, a ratchet member movable with the shaft, a plurality of lugs in the said frame disposed in the path of movement of said ratchet member, and resilient supporting means embracing the said shaft 75 adjacent the ratchet member to hold the latter in contact with said lugs.

24. An actuating mechanism of the class described comprising a winding shaft having a crank disposed at its upper end, a sleeve disposed about the said shaft and having a toothed escapement wheel at its lower end, a coil spring disposed about the said sleeve and attached at opposite ends to the crank and escapement wheel respectively, an escapement beam having pallets to be engaged by the teeth of the escapement wheel, a frame supported loosely on said shaft and provided with bearings in which the said beam is mounted, and an upright 80 pendulum carried by said beam, the said escapement wheel having one edge of its teeth inclined in the direction of rotation thereof whereby alternate engagement of the inclined edges with said pallets will 85 cause the beam and pendulum to operate.

25. A dancing toy comprising a toy figure and motor and winding means therefor, said motor and winding means comprising a winding shaft having a crank disposed at its upper end, a sleeve disposed about said shaft and having a toothed escapement wheel at its lower end, a coil spring disposed about the said sleeve and attached at opposite ends to the crank and escapement wheel respectively, an escapement beam having pallets to be engaged by the teeth of the escapement wheel, and a frame supported loosely on said shaft and provided with bearings in which the said beam 100 is mounted.

26. A dancing toy comprising a toy figure and motor and winding means therefor housed by the figure, said motor and winding means comprising a winding shaft having a crank disposed at its upper end, a sleeve disposed about said shaft and having a toothed escapement wheel at its lower end, a coil spring disposed about the said sleeve and attached at opposite ends to the crank and escapement wheel respectively, and means operated by the escapement wheel for setting the figure into dancing 105 action.

In testimony whereof I have affixed my 115 signature.

T RAYMOND ARDEN.
